UNITED STATES PATENT OFFICE.

BERT CROSBY, OF DAYTON TOWNSHIP, BUTLER COUNTY, IOWA.

TILING.

No. 898,560.

Specification of Letters Patent. Patented Sept. 15, 1908.

Application filed January 23, 1907. Serial No. 353,714.

To all whom it may concern:

Be it known that I, BERT CROSBY, a citizen of the United States, residing at Dayton township, in the county of Butler and State of Iowa, have invented certain new and useful Improvements in Tiling; and I do hereby declare the following to be a full, clear, and exact description of the invention, such as will enable others skilled in the art to which it appertains to make and use same, reference being had to the accompanying drawings, and to the letters and figures of reference marked thereon, which form a part of this specification.

15 This invention relates to new and useful improvements in tiling, and the object of the invention is to produce an apparatus of this nature whereby the sections may be prevented from lateral movement, affording 20 means for keeping out foreign or other matter likely to pass between the joints.

The invention consists further in other details of construction and combinations and arrangements of parts which will be herein- 25 after fully described and then specifically defined in the appended claims.

I illustrate my invention in the accompanying drawings, in which:—

Figure 1 is a perspective view of a tile 30 made up of two sections and in accordance with my invention. Fig. 2 is a similar view showing another section of tile adapted to be connected to the tile shown in Fig. 1. Fig. 3 is a detail perspective view of the upper section of the tile, and Fig. 4 is a cross sectional view through the two sections of a tile.

Reference now being had to the details of the drawings by letter, A designates the lower section of the tile having a reinforced 40 bottom A', flat upon its under edge. Said section is substantially semi-cylindrical upon its inner surface and the outer faces of its sides are slightly convexed in contour.

B designates the upper section of the tile 45 which has a reinforced portion D extending about the marginal edge thereof and said reinforced portion projects over one end of the section and the two longitudinal sides, forming flanges or hoods which are adapted to engage 50 the outer circumference of the lower section adjacent to its upper end; when the two sections of the tile are adjusted together, as shown in Figs. 1, 2 and 4 of the drawings. Said hoods, it will be noted, project beyond the longitudinal 55 edges of the upper section and also beyond one end, one end of the upper section

having a shoulder for the reception of the hood which projects from the adjacent section. These hoods are slightly concaved on their inner faces and adapted to conform to 60 the curvature of the outer surfaces of the lower section and, by the joint thus formed, the sections may expand under any internal force within the tiling and, owing to the particular manner in which the hoods engage the 65 lower section, the inflow of water from the outside will be effectually prevented. The reinforced portion formed upon the upper section, at one end thereof is spaced apart therefrom in order to receive the flange of 70 the opposite end of another tile, thereby covering the joints through which material would otherwise fall in the event of the tiles being slightly displaced. The concaved flange projecting beyond the end of the tile 75 section and also beyond the longitudinal edges thereof not only serve to hold the sections against lateral movement but also hold the sections in alinement with each other. By reinforcing the portions of the upper section of the tile adjacent to its joints, it will be noted that a substantial tile is afforded which will resist heavy pressure which might come upon the same for any purpose.

By the provision of a tile made as shown 85 and described, it will be noted that the sections may be nested together for storage or shipping purposes, thereby economizing in space.

What I claim is:—

A tile made up of an upper and a lower section, the lower section having flat bottoms with their upper surfaces semi-cylindrical, the outer surfaces of the lower sections being slightly convexed, the upper sections having 95 flanges projecting beyond one end thereof and the longitudinal edges of the section, the flanges upon the longitudinal edges of the upper section being slightly concaved and conforming to the convexed surface of the 100 lower section against which they bear, the outer surface of one end of each upper section having a shoulder for the reception of the projecting flange of an adjacent section, said flanges being raised above the surface of the 105 upper section, as set forth.

In testimony whereof I hereunto affix my signature in the presence of two witnesses.

BERT CROSBY.
